COMBINED ASH TRAY AND CANDLE HOLDER OR SIMILAR ARTICLE

Harold C. Carlstead, Flossmoor, Ill.

Application January 10, 1955, Serial No. 33,900

Term of patent 7 years

(Cl. D85—2)

Figure 1 is a perspective view of a combined ash tray and candle holder or similar article, showing my new design; and

The opposite perspective view, not shown, has substantially the same appearance as the perspective view shown in Figure 1.

I claim:

The ornamental design for a combined ash tray and candle holder or similar article, as shown and described
